BELT BUCKLE

Harold C. Vaisey and John R. Whitehouse, Rochester, N. Y., assignors to Hickok Manufacturing Co. Inc., Rochester, N. Y., a corporation of New York

Application February 7, 1950, Serial No. 142,776

4 Claims. (Cl. 24—191)

1

This invention relates to belt buckles.

The invention more particularly relates to belt buckles that are adapted to be attached to the end of leather or other belts for personal wear.

The invention comprehends a belt buckle which includes a back plate with right-angularly forwardly extending top and bottom flanges integral therewith and a flange or an extension of each of the said flanges providing a rail or guide for individual initials that are adapted to be slid on the rail or guide and there being means to maintain the initials in their proper position with respect to the back plate and form a passageway for the free end of the belt in said passageway and the back plate having pivotally attached thereto a ratchet or cam belt-secur ing means having integral therewith a bail to which one end of the belt is secured. In this particular buckle, the aforesaid initials constitute substantially the entire visible front surface of the buckle when viewed in full front elevation.

It is an object of our invention to provide a belt buckle wherein substantially the entire front visible face thereof is in the form of initials, or the like, or other insignia which can be readily selected and applied to the belt buckle and likewise readily fixedly secured thereto, without requiring the use of expensive tools or a trained jewelry worker for assembling the initials with the buckle.

Another object of our invention is to provide a relatively simple and rather inexpensive, yet effective, ornamental belt buckle of the ratchet clamping type and wherein substantially the entire front visible face thereof is in the form of initials that may be selected and applied and held in their proper position and relationship with respect to the buckle proper.

Further objects of the invention are to provide a belt buckle wherein initial members are detachably slidably incorporated in the structure thereof and constitute substantially the entire front of the same, and the provision of simple, efficient means to maintain the initial members in fixed position.

With these and other objects in view, the invention consists in the construction and novel combination and arrangement of parts herein-after fully described, illustrated in the accompanying drawings and pointed out in the claims hereto appended, it being understood that various changes in the form, proportions, and minor details of construction, within the scope of the claims, may be resorted to without departing from the spirit or sacrificing any of the advantages of the invention.

2

In the drawings:

Fig. 1 is a front elevational view of the buckle attached to the belt, a portion of the belt only being shown;

5 Fig. 2 is a perspective view of the buckle as attached to the belt as shown in Fig. 1;

Fig. 3 is an exploded perspective view showing the ratchet clamping means and the back plate, with the flanges integral therewith;

10 Fig. 4 is a rear elevational view of the buckle;

Fig. 5 is a longitudinal sectional view taken substantially along the lines 5—5 of Fig. 4 and showing the ratchet clamping means in its clamping position;

15 Fig. 6 is a view similar to Fig. 5 but showing the ratchet clamping means in its non-clamping position;

Fig. 7 is a perspective view of one of the initials showing the grooves by which it is mounted on the extensions of the flanges of the buckle;

20 Fig. 8 is a top plan view of the initial shown in Fig. 7; and

Fig. 9 is an exploded perspective view of a slightly modified form of the invention.

25 The buckle consists of a back plate 10 which is substantially rectangular in shape. Integral upper and lower flanges 11 and 12, respectively, which extend substantially at right angles outwardly from the back plate 10, it will be seen by referring to Fig. 3, have end portions 13 and 14, respectively, which project beyond the inner edge 15 of the back plate thus providing a sort of cut-out or cut-away portion in which the ratchet clamping means is positioned and held and operates.

30 The back plate 10 has integral therewith suitable substantially cylindrical bearings or eyelets 16 and 17 which extend outwardly beyond the plane surface of the back plate 10. The said flanges 11 and 12 have inwardly bent or disposed rails 18 and 19 integral therewith and the edge portions 20 of these rails or guides for the initials hereinafter mentioned are substantially parallel with the inner surface of the back plate 10 and, of course, spaced therefrom, and are in substantially vertical alignment with each other. It is to be specifically noted that the aforesaid flanges 11 and 12 taper in cross-sectional width

40 from the end 21 thereof to the other end 22 or it might be said that these flanges diverge from the ends 21 thereof to the other ends 22 for the purpose later named. The flanges 11 and 12 are provided at each end thereof with an integral 45 stop tab 23 and a locking tab 24 which tabs are capable of being bent at a right-angle to these

flanges to effectively maintain the initials or other indicia hereinafter referred to in their relationship with the back plate and the flanges constituting the buckle.

The clamping means for the free end of the belt is denoted generally at 25 and consists of a preferably polygonal body portion 26 having flat ends 27 and preferably integral pins or pintles 28 that project outwardly from these flat portions and which pins are in vertical alignment with each other. The serrated gripping portion of the clamping member is denoted at 29 and, as shown, is of greater length than the said body portion 26 and of substantially the same length as the body portion and the pins that are attached thereto. The body portion of the clamping member merges into a bail or the like 30 which has an opening 31 therein and this bail and body portion are substantially at right angles with respect to the serrated gripping element 29.

The combined clamping and bail means is attached to the back plate of the buckle by simply positioning the pins or pintles 28 in the respective cylindrical bearings 16 and 17 and then clinching over these bearings to maintain the pins of the said member in its proper pivotal or movable arrangement and relationship. These cylindrical bearings 16 and 17, as aforesaid, are integral with the back plate 10 and are capable of being expanded to position the pins therein and, by simply bending these bearings, the pins are securely held in position.

The initials 32 and 33, which are in the form of letters of the alphabet "R" and "H," but which may be of any of the other letters of the alphabet or suitable indicia, are preferably made of one piece and are of metal or the like and the edges or outline of the initials are preferably beveled as shown at 34 and the surface in between the beveled outline 35 is preferably concave. The upper and lower end portions of each initial or other indicia that is utilized to be placed on the rails of the back plate of the buckle have open-ended grooves 36 and 37 respectively therein. Where the initial or other indicia is like the letter "R" depicted in the drawings, and includes a rounded side edge portion 38, the upper portion of the wall that constitutes the groove 36 is extended as at 39 so that the end thereof is substantially in vertical alignment with the maximum width of the side edge of the initial. This extension 39 is, in effect, a means which enables another initial to abut thereagainst or, when the initial such as "R" is the second initial to be inserted on the rails 18 and 19, the extension serves as a means whereby the tabs 24 at the ends of the flanges 11 and 12 serve to abut against and maintain the initials on the rails of the back plate so that they will not move or slide or rattle.

In the modification of the invention, as shown in Fig. 9, the construction, except for the bearings for the pintles or pins in the bearing member is identical with the structure shown in the other figures of the drawings.

In this modification, however, the bearings for the pintles, rather than being formed from integral extensions of the back plate 10, are, in fact, apertured extensions 40 and 41 of the flanges 11 and 12 respectively. In this modification, the pintles or pins 42 are somewhat shorter than the pins or pintles 28 and obviously and necessarily so because these pintles simply are disposed in the apertures 43 in the extensions 40 and 41 and the combined bail and clamping member operates in the same manner as it does in the con-

struction of the buckle as shown in the other figures of the drawings.

One end of an apparel or the like belt 44 is reversely bent upon itself and extends through the bail 30 and is suitably stitched as at 45 in order to secure the buckle to that end of the belt. The other free end of the belt 46 passes through the tapered passageway 47 and is clamping held in any desired position therein by the ratchet gripping means 29 on the combined bail and gripping element, the gripping position of the said ratchet means being clearly shown in Fig. 5 of the drawings and in Fig. 6 thereof, the ratchet means is shown in the non-gripping position.

Due to the tapering effect of the upper and lower flanges 11 and 12 that are integral with the back plate 10, it is clear, in viewing Figs. 2, 5 and 6, that the passageway 47 that is formed between the inner face 48 of the back plate 10 and the inner faces 49 of the initials 32 and 33, tapers in cross-sectional width from the clamping end of the buckle to the other end thereof. Thus, in the wider space which is at the clamping end of the buckle, sufficient area is provided within which the combined clamping and belt-gripping elements are arranged and operated, and, at the reduced end of the passageway, it will be clear, there is sufficient clearance so that the belt can protrude beyond this end of the buckle and be held snugly in the passageway due to the reduced width of this passageway at the end of the buckle opposite where the clamping of the belt is effected.

It is to be definitely understood that the letters "R" and "H" are merely exemplary of the other letters of the alphabet or other suitable indicia that may be attached to the belt buckle and constitutes substantially the entire front face thereof.

It is obvious that, when the grooves in the initials are aligned with the rails 19 and 18, these initials can be slid on the rails, or at least the first one, as far as it will go until stopped by the stopping tabs 24, one of which is at the top and bottom end of the flanges 11 and 12.

After the second initial, which is the letter "H" in this case, is applied slidably to the rails, the tabs 23 are then bent at a right angle with respect to the flanges 11 and 12 at the ends thereof and these tabs 23 effectively serve to lock the two initials in their proper arrangement and position and relationship with respect to the back plate 10. When the tabs 24 and the tabs 23 are thus bent at right angles with respect to the ends of the flanges 11 and 12, the initials will be securely held in position and prevented from rattling or moving relative to the back plate 10 or the flanges 11 and 12 and also the guide rails 18 and 19.

What we claim is:

1. A belt buckle comprising a rear member including a substantially rectangularly-shaped back plate having upper and lower edges with integral flanges extending substantially right-angularly outwardly of said edges and said flanges being in substantially spaced parallelism, extensions of the said flanges in the form of integral rails which rails are substantially in vertical alignment with each other, the said flanges extending beyond one end edge of the back plate at the top and bottom thereof and having at each of their respective ends tabs, plate-like initial members having grooves in the upper and lower edges thereof, said initial members being mounted on

the said rails, the said tabs serving to engage an end portion of each of the initial members at the top and bottom thereof and serving to secure the initial members in position on the rails and with respect to the back plate, bearings integral with the rear member and inwardly of the extending ends of the said flanges, and a combined bail and clamping member having pins positioned in the bearings allowing of pivotal movement of this member, and the inner faces of the initial members and the inner face of the back member providing a passageway for the disposition therein of the free end of the belt and the bail serving as a means to have the other end of the belt secured thereto.

2. A belt buckle as defined in and by claim 1 wherein the said flanges taper from one end edge to the opposing end edge thus provide a tapering passageway through which the free end of the belt extends.

3. A belt buckle comprising a substantially rectangular shaped back plate member having integral flanges extending forwardly from its upper and lower edges at substantially a right angle thereto, said flanges having inwardly extending rail extensions disposed substantially in transverse alignment with each other, means for attaching one end of a belt to said rear plate member at one end thereof, a front plate-like member in the form of an initial or the like having a groove in the upper and lower edges thereof to slidably engage said rail extensions, said plate-like member being engaged with said rail extensions and supported thereby in opposed spaced relation with the back plate member to provide therewith a passageway to receive and permit sliding adjustment therein of the end portion of a belt, said front initial member being of a length substantially equal to the width of the back plate member and constituting substantially solely the entire visible front face of the buckle, and means for fixedly and non-remov-

ably maintaining the said front initial member on said rail extensions.

4. A belt buckle comprising a substantially rectangular shaped back plate member having integral flanges extending forwardly from its upper and lower edges at substantially a right angle thereto, said flanges having inwardly extending rail extensions disposed substantially in transverse alignment with each other, means 5 for attaching one end of a belt to said rear plate member at one end thereof, front plate-like members in the form of initials each having a groove in the upper and lower edges thereof to slidably engage said rail extensions, said plate-like members being engaged with said rail extensions and supported thereby in opposed spaced relation with the back plate member to provide therewith a passageway to receive and permit sliding adjustment therein of the end portion of a belt, 10 15 20 25 said front initial members being of a length substantially equal to the width of the back plate member and constituting substantially solely the entire visible front face of the buckle, and tab extensions on the ends of said flanges for securing said front initial members on said rail extensions.
